UNITED STATES PATENT OFFICE.

WASHINGTON D. KEYES, OF KITTANNING, PENNSYLVANIA.

APPARATUS FOR DELIVERING GLASS.

SPECIFICATION forming part of Letters Patent No. 695,156, dated March 11, 1902.

Application filed August 27, 1900. Serial No. 28,138. (No model.)

To all whom it may concern:

Be it known that I, WASHINGTON D. KEYES, a citizen of the United States, residing at Kittanning, in the county of Armstrong and 5 State of Pennsylvania, have invented new and useful Improvements in Apparatus for Delivering Glass, of which the following is a specification.

This invention relates to the removal of 10 molten glass from a tank or other furnace and its delivery for working, as to a casting-table.

The object of the invention is to provide apparatus for effecting the direct transfer and delivery of glass from the reducing and refining apparatus to the casting-table, thereby 15 doing away with the portable fining-pots universally used in the manufacture of plate-glass. In the preparation of glass as now practiced the batch is melted and refined in 20 one and the same pot, or it is reduced to molten state in a melting-tank and drawn off into pots and refined by placing the pots in a fining oven or furnace. When by either 25 process the glass is in proper condition, it is poured from the pots onto the casting-table. 30 These old methods of manufacture are indirect and necessitate the employment of fragile and expensive apparatus. However, as before stated, pots are universally used, as 35 prior to my invention no adequate mechanism has been devised for removing and delivering the glass which did not so agitate it as to render it unfit for working. My improved apparatus obviates these difficulties 40 and at the same time increases the production by effecting a direct transfer or delivery of the glass without undue agitation.

In the accompanying drawings is illustrated 45 apparatus constructed in accordance with my invention.

Figure 1 is a side elevation of the same, partly in section, the position of the ladle just before filling being shown in solid lines and the position thereof over the casting-table before discharging shown in dotted lines. Fig. 45 2 is a plan view of Fig. 1. Figs. 3 and 4 illustrate the movement of the ladle within the refining end of the tank.

Referring to the drawings, 2 is the melting- 50 tank, 3 the refining end or compartment thereof, and 4 the floats.

5 represents elevated tracks at the front

and outside of compartment 3 and extending transversely thereof, and 6 is a crane movable on the tracks. Mounted on the crane 55 is trolley 7, which carries the two hydraulic or other cylinders 8, to which actuating fluid may be supplied in any suitable manner.

9 represents piston-rods depending from the cylinders. At the lower ends of the rods 60 are bearing-collars 10, in which is rotatably mounted the horizontally-elongated bar 11, provided at one end with handles 12 and at the opposite end carrying ladle 13. The ladle 65 is elongated and semicylindrical in shape, with its end walls secured on bar 11, which extends therethrough, and its body portion curved concentrically to said bar. The ladle is formed of thin metal and its longitudinal edges form cutting edges, the advancing edge 70 entering the molten glass when the ladle is turned in the operating of filling without disturbing or displacing the glass while turning therein, owing to its concentric shape. The stroke of the two piston-rods is identical 75 and in extent corresponds to the radius of the ladle. The ladle is introduced through opening 3' into compartment 3 in inverted position, with bar 11 in lowermost position and just clearing the bottom of opening 3', all as 80 shown in full lines in Figs. 1 and 3. With the ladle thus positioned over float or skimmer 14 bar 11 is slowly rotated, and the ladle is thus turned concentrically into the refined glass, as shown in dotted lines in Fig. 3, and 85 the movement is continued until the ladle reaches an upright position, (shown in full lines in Fig. 4,) when it is filled. Pistons 9 are then moved to the upward limit of their 90 movement or stroke, lifting the bar 11 and ladle to position shown in dotted lines in Fig. 4. The ladle is then withdrawn, the trolley 95 moving outward over the crane. The latter is then moved, carrying the ladle laterally over the casting-table 15, when the ladle is again lowered, the piston-rods moving downward the limit of their movement, thus positioning the ladle as close as is practicable to the table, and thereby minimizing the drop 100 of glass thereon when discharged by a gradual rotation of bar 11 and the ladle. The inverted ladle is then raised and righted, and the crane is moved backward to original or charging position. The trolley is then moved

to position the ladle over water-bath 16, when the ladle is again lowered and immersed in the bath by being given a complete rotation, thus thoroughly cleansing it of any glass that may have adhered thereto from the previous operation and preparing it for the next dipping operation. The ladle is then moved into refining-compartment 3, being in lowered and inverted position ready for the next filling or charging operation.

The ladle is manipulated by one, two, or more men at the handle end of bar 11. I do not restrict myself to the means here shown for effecting the longitudinal and lateral movement of the ladle-carrying bar, as the same may be accomplished in a variety of ways, nor do I restrict myself to the relative arrangement of the refining-chamber, bath, and casting-table, as the same may be varied as circumstances may require. The glass should be in condition for casting before being removed from the refining-compartment. If, however, its temperature is too high, it may remain in the ladle until sufficiently cool.

25 The circular or concentric movement of the ladle in the refined glass causes the same to fill with no perceptible agitation, and when the filled ladle is lifted the glass remaining in the refining-chamber equalizes or assumes 30 a uniform level without injurious results. The operation of filling the ladle is, in effect, a concentric cutting or shearing of the glass, and the charge to be withdrawn is encompassed quietly and without displacement. 35 The ladle is moved to discharging position over the casting-table with the least possible jolting or jarring and is maintained in horizontal position by the hydraulic lifts. The ladle is formed of a metal, such as platinum, 40 which will resist the intense heat to which it is subjected.

Having thus fully described my invention, what I claim as new, and desire to secure by Letters Patent, is—

45 1. Improved glass-delivering mechanism, comprising a portable ladle adapted to rotate on a horizontal axis, means for maintaining

the ladle-axis constantly in a horizontal plane, mechanism for raising and lowering the horizontally-maintained ladle and means for limiting the throw of said mechanism to a distance equal to the radius of the ladle, substantially as shown and described. 50

2. Improved glass-delivering apparatus, comprising a refining-chamber having an opening, a ladle-support, a ladle on the support adapted to rotate on a horizontal axis, a ladle-bath in line with the chamber-opening, means for maintaining the ladle-support constantly in horizontal position, means for 60 moving vertically the horizontally-maintained ladle-support, and mechanism for moving the support and ladle to position over the bath and from thence to discharging position, substantially as shown and described. 65

3. In improved glass-delivering mechanism, the combination with a refining-chamber provided with an opening, and a ladle-bath exterior to the refining-chamber, of a ladle, a rotatable ladle-support to which the 70 ladle is fixed, means for maintaining the ladle-support constantly in horizontal position, means for vertically moving said support, and mechanism for transporting the ladle and its support from the refining-chamber to 75 the bath, and from the latter to position for discharging, substantially as shown and described.

4. In improved glass-delivering apparatus, the combination with the ladle-support and 80 the ladle on the support, of two power-cylinders having their piston-rods secured to the support and sustaining the same in horizontal position, the piston-rods serving to move the support and ladle vertically, substantially 85 as shown and described.

In testimony whereof I have hereunto set my hand in presence of two subscribing witnesses.

WASHINGTON D. KEYES.
